UNITED STATES PATENT OFFICE.

EMIL ZETTLER, OF CHICAGO, ILLINOIS, ASSIGNOR TO JAMES B. CLOW & SONS, OF CHICAGO, ILLINOIS, A CORPORATION OF ILLINOIS.

DESIGN FOR A GAS HEATER.

Application filed January 30, 1922. Serial No. 421. Term of patent 14 years.

To all whom it may concern:

Be it known that I, EMIL ZETTLER, a citizen of the United States, residing at Chicago, in the county of Cook and State of Illinois, have invented a new, original, and ornamental Design for a Gas Heater, of which the following is a specification, reference being had to the accompanying drawing, forming part thereof.

In the drawing, the figures are front and side elevations of a gas heater embodying my new design.

I claim:

The ornamental design for a gas heater as shown.

In witness whereof, I hereunto subscribe my name this 27th day of January, 1922.

EMIL ZETTLER.
